US0D1029704S

(12) **United States Design Patent** (10) **Patent No.:** **US D1,029,704 S**
(45) **Date of Patent:** **** Jun. 4, 2024**

(54) **GRILLE FOR AUTOMOBILE OR REPLICA THEREOF**

(71) Applicant: **ASTON MARTIN LAGONDA LIMITED**, Warwick (GB)

(72) Inventors: **Antonino Lo Re**, Warwick (GB); **Sam Holgate**, Warwick (GB)

(73) Assignee: **Aston Martin Lagonda Limited**, Gaydon (GB)

(**) Term: **15 Years**

(21) Appl. No.: **29/834,636**

(22) Filed: **Apr. 13, 2022**

(30) **Foreign Application Priority Data**

Oct. 19, 2021 (EM) 008670426-0006

(51) **LOC (14) Cl.** **12-16**

(74) *Attorney, Agent, or Firm* — Dorsey & Whitney LLP

(57) **CLAIM**

The ornamental design for a grille for automobile or replica thereof, as shown and described.

DESCRIPTION

FIG. 1 is a front elevation view of an embodiment of a grille for automobile or replica thereof in accordance with the present design;

FIG. 2 is a left elevation view thereof;

FIG. 3 is a top plan view thereof;

FIG. 4 is a left rear perspective view thereof;

FIG. 5 is a left front perspective view thereof;

FIG. 6 is a rear elevation view thereof; and,

FIG. 7 is a right elevation view thereof.

The dot-dash lines in the illustrations depict the boundary of the claimed design. The even dash lines depict environmental structures that form no part of the claimed design.

1 Claim, 7 Drawing Sheets
